(57) **CLAIM**

The ornamental design for a scale, as shown and described.

DESCRIPTION

The scale to which our design is applied will function as follows: When a person stands on the scale, the person's weight and the person's body fat rate can be calculated and displayed on the display.

FIG. 1 is a front view of a scale according to our novel design;

FIG. 2 is a rear view of the scale of FIG. 1;

FIG. 3 is a right side view of the scale of FIG. 1, the left side view thereof being symmetrical thereto;

FIG. 4 is a plan view of the scale of FIG. 1;

FIG. 5 is a bottom view of the scale of FIG. 1; and,

FIG. 6 is a plan view of the scale of FIG. 1 with the display being switched on.
